UNITED STATES PATENT OFFICE.

CHARLES S. EDWARDS, OF PRINEVILLE, OREGON.

PLIERS.

1,266,567.

Specification of Letters Patent. Patented May 21, 1918.

Application filed June 18, 1917. Serial No. 175,422.

To all whom it may concern:

Be it known that I, CHARLES S. EDWARDS, a citizen of the United States, and residing at Prineville, in the county of Crook and 5 State of Oregon, have invented a new and Improved Pliers, of which the following is a specification.

This invention has reference to improvements in pliers and particularly to that type 10 of pliers in which is included a stationary jaw on one handle member, a slideable jaw co-operative with the other jaw, and lever and rack connections for the slideable jaw for effecting the desired gripping action 15 when closing the jaws together.

Primarily my invention has for its purpose to provide an improved pliers of the general type stated, in which the parts are especially designed, in a simple and compact 20 manner, for exerting great leverage power, and the said parts arranged for being quickly adjusted to provide for effectively increasing or diminishing the power of the pliers to adapt them for special kinds of 25 work, as conditions may require.

Again, my invention has for its purpose to provide an improved construction of pliers, of the type generally stated, in which is included means for shifting the fulcrum 30 for the lever and rack devices, whereby the capacity of the pliers is increased or diminished and the operating parts are correlatively so constructed that they may be readily assembled for use, and while the 35 said parts are specially well adapted for use in pliers they may be readily modified for use in wire cutters, pincers, dies and various tools of similar nature in which great handle leverage is required.

40 With other objects in view, that will hereinafter appear, my invention embodies the peculiar features of construction and combination of parts that constitute my improved pliers, all of which will be explained in detail, specifically pointed out in the appended claims and illustrated in the accompanying drawing in which:

Figure 1 is a perspective view of a pair of pliers embodying my invention.

50 Fig. 2 is a longitudinal section thereof, parts being in side elevation, the jaws being shown in their partly open position.

Fig. 3 is a view similar to Fig. 2, the jaws being at the fully closed position.

Fig. 4 is a similar view, the jaws being at 55 their open position.

Fig. 5 is a detail cross section taken on the line 5—5 of Fig. 1, looking in the direction of the arrow.

Fig. 6 is a top view of the main head or 60 jaw.

Fig. 7 is a perspective view of the shift-able bearing member.

Fig. 8 is a perspective view of a toggle or stirrup-like hanger that constitutes one of 65 the pivotal connections for the movable lever handle.

Fig. 9 is a detail view of the slideable roller and pin members that constitute the main pivot bearing for the movable handle lever. 70

Fig. 10 is a perspective view of the movable jaw.

Fig. 11 is a detail view indicating a modified construction of the movable jaw.

Fig. 12 is a detail view of the operating 75 lever or handle.

In the practical arrangement thereof, my improved pliers includes a main and relatively stationary body having a jaw, and a movable body portion or jaw, each of 80 which has an integral or otherwise fixedly connected handle or lever member, the two lever members being so arranged whereby they may be readily grasped and closed together by hand.

The main or body jaw, hereinafter termed the "fixed jaw" 17 is located at that end of the body 1, opposite a handle or lever member 19, integral with such body, as is clearly shown in Fig. 1. 15 designates a vertical slot formed in the body and the jaw 17 and which merges with a longitudinal recess or slotway 2 that opens, through the front and rear edges of the said body, as shown.

85 Each of the side cheeks of the body 1 has a vertically elongated slot 4 that form vertical guideways for the roller bearings 5—5, removably mounted on a pin axle 6 that constitutes the main or upper fulcrum for an operating lever 20, the latter having a transverse aperture 10 through which the said axle 6 extends. The said axle 6 and the rollers 5—5 are held in proper position by a cap screw 12, see Fig. 5.

100 3 designates a sliding or movable jaw and the same has a vertical guide rib 30 at its front edge for engaging a guide groove

85

90

95

105

15^a that merges with the slot or opening 15 and the said movable or sliding jaw 3 has a toothed rack 14 on the rear face which engages with a sector rack 13 formed on the 5 operating lever or handle 20.

21 designates a sliding member whose upper end is formed with a pair of oppositely disposed lugs or bifurcated extensions 27—27, each of which has an inwardly projected lateral stud 7—7, the purpose of which will presently appear.

The rear side of the member 21 has a horizontally concaved rack face 22 that engages with an adjusting worm gear or screw nut 15 23 mounted in a socket 25 formed in the body 1 and which is held in the operative position by a screw stud 24, as is clearly shown in Figs. 1, 2, 3 and 4 of the drawings, by reference to which it will be seen that the 20 body 1 has a recess 25 in each of its side or cheek portions in which the screw nut 23 projects for being conveniently turned by thumb and finger manipulation.

A toggle or hanger connection joins the 25 slideable member 21 and the operating lever handle 20 and the said connection consists of a pair of links 8—8 whose upper ends are apertured for pivotally sustaining them on the inturned lugs 7—7 on the slideable 30 member 21 and whose lower ends are joined by a stud pin 9, which, in assembling the parts for use, also passes through an aperture 11 in the lower end 11^a of the head portion of the lever which has the sector 35 rack 13, the pin 9 forming, as it were, the lower pivot of the movable lever 20.

From the foregoing description taken in connection with the drawings the complete construction of my invention will be readily 40 apparent. The operation of the tool may be described as follows: Separating the handles 19—20 causes the movable jaw 3 to open from the main or relatively stationary jaw 17, the sector 13 during the closing motion of the lever 20 being kept in mesh with the rack face 14 by the upper pivot 6 and the rollers 5—5 guided in the slots 4—4, it being understood that a maximum width or opening between the said jaws is obtained by a greater spread of the handles 50 which changes the fulcrum of the lever 20 which now swings backwardly on the hangers 8.

The closing of the handles brings the jaws 55 together, the power acting through the two pivots 6 and 9.

By reason of making the operating lever as described and mounting the movable jaw and providing the connections that join the 60 movable jaw with the lever in the manner shown, a greater leverage is obtained than can be produced in the ordinary forms of pliers, for the reason that the power acts through a joint obtained through the hangers 8 and that portion of the working end of

the movable handle between the pivots 9 and 6, the leverage being greatly increased as the jaws are nearly closed and the fulcrum points 9, 6 and 7 are brought into a substantially straight line.

70

The capacity of the pliers is increased or diminished by adjusting the sliding member 21 up or down so as to change the position of the fulcrum 7, the sliding member moving in the guide slots 26 provided therefor in the main body, as before stated.

75

In actuating the levers 19 and 20, a compound action is exerted that effects the extent of travel of the movable jaw, since there is a movement which the swing of the handle causes when acting through the sector and pivot 6 alone, and also an upward thrust effected by the toggle joint or hanger members 8.

80

Instead of having a friction bearing between the rack portions of the movable jaw and the edges 15^b of the groove 15 in the main body, the movable jaw may be provided with roller bearings, such as shown in Fig. 10 for engaging with the said shoulders 15^a.

85

What I claim is:

1. In an implement of the character described, a body having a relatively fixed jaw and handle, a moving jaw slidably mounted on the said body for coöperating with the relatively fixed jaw, said slideable jaw including a rack face, a lever having a rack sector for engaging the rack face of the movable jaw, a pivotal connection for the lever mounted and having vertical movement on the body, a bearing member shiftably mounted on the said body, a link connection that joins the said bearing and the lever, and means mounted on the body for sliding the bearing whereby to adjust the pivotal connection for the lever.

100

2. In an implement of the character described, a body having a relatively fixed jaw and handle, a moving jaw slidably mounted on the said body for coöperating with the relatively fixed jaw, said slideable jaw including a rack face, a lever having a rack segment for engaging the rack face of the movable jaw, a pivotal connection for the lever mounted and having vertical movement on the body, a bearing member shiftably mounted on the said body, a toggle link connection that joins the said bearing and the lever, means mounted on the body for setting the bearing whereby to adjust the fulcrum for the lever, said means including a rack surface on the shiftable bearing and a finger controlled worm gear engaging the said rack surface.

110

3. In a pair of pliers, the combination of a body having a relatively fixed jaw and handle, a movable jaw slideable on the body, a lever handle having a gear segment, the movable jaw having a rack face engaging

115

120

125

130

the said gear segment, a fulcrum for the handle slidable on the body, a bearing slidably mounted on the said body, toggle links that join the bearing with the lower end of 5 the lever handle and a screw nut and rack for adjusting the fulcrum points for the lever whereby to increase or diminish the capacity of the jaws.

4. An implement of the character described 10 comprising a body having a longitudinal slotway extending through the front and rear edge thereof, a vertical guide groove at each end of the said slotway, said body portion including a relatively fixedly held 15 jaw and handle, a movable jaw slidably mounted in the guide groove at the outer end of the body, and a shiftable bearing slidably mounted in the other guide groove in the body, the said movable jaw and the 20 movable bearing each having a rack face, a lever including a head having a segmental gear for engaging the rack face of the movable jaw, a cross pivot at the lower end of the lever, a cross pivot at the upper end of the 25 shiftable bearing, a toggle link connection that joins the pin in the upper end of the shiftable bearing and the cross pivot in the lower end of the lever and a main fulcrum on the lever vertically shiftable on the said 30 body.

5. In an implement of the character described, a body having a relatively fixed jaw

and handle, a movable jaw slidably mounted on the body for coöperating with the relatively fixedly held jaw, and lever and rack 35 mechanism for effecting movement of the sliding jaw, said mechanism including an adjustable fulcrum and means for adjusting the said fulcrum to provide for the very slightest as well as wide adjustments of the 40 movable jaw.

6. In an implement of the character described, a body having a relatively fixed jaw and handle, a movable member for coöperating with the fixed jaw and lever and rack 45 mechanism for effecting movement of the movable member, the said mechanism including toggle connection whereby to provide for increasing the clamping effect of the relatively fixed jaw and the movable 50 member, and means operative while the implement is applied to the work for effecting the adjustments of the fulcrum.

7. In pliers, a body having a relatively fixed jaw and handle, an opposing jaw having a rack and slidably mounted on the body for coöperating with the fixed jaw and lever and sector mechanism for effecting movement of the said sliding jaw without disengaging the sector from the said jaw, the said 60 mechanism including a toggle connection, whereby to provide for increasing the clamping effect of the opposing jaw.

CHARLES S. EDWARDS.
